UNITED STATES PATENT OFFICE.

GEORGE B. SPRING, OF NEWTON HIGHLANDS, MASSACHUSETTS.

REINFORCEMENT FOR POLES.

Application filed August 14, 1925. Serial No. 50,820.

This invention relates to a means for reinforcing telephone poles, telegraph poles and other similar poles.

After a wooden pole of this nature has been in use for several years it begins to show signs of weakness at the surface of the earth, this weakness being caused by the decay in the pole occasioned by the changes in the degrees of moisture to which the pole is subjected at the surface of the earth.

It is an object of my present invention to provide an improved reenforcement for wooden poles which may be applied to the pole when it begins to decay or to show signs of weakness and by means of which the life of the pole can be materially lengthened.

My improved reenforcement can, if desired, be applied to the pole when it is set so that it will at all times be operative to reenforce and strengthen the pole.

The reenforcing means embodying my invention comprises two or more reenforcing members each formed of two angle iron elements that are rigidly connected together to form a member having a general T shape in cross section, one leg of each member resting against the pole and the other leg extending outwardly or radially from the pole.

The device also includes a plate situated between the radial legs, one edge of which extends beyond the legs that rest against the pole and thus forms a rib that is embedded in the pole, and the other edge of which extends beyond the radial legs of the angle iron and forms an anchoring wing that is embedded in the soil and that serves to anchor the reenforcing members in position. These two members are clamped to the pole by means of a suitable clamping iron.

In order to give an understanding of my invention I have illustrated in the drawings a selected embodiment thereof which will now be described after which the novel features will be pointed out in the appended claims.

Fig. 1 is a view illustrating my improved reenforcing means in use for reenforcing a pole, a portion of one of the members being broken out to better show the construction;

Fig. 2 is a section on the line 2—2, Fig. 1;

Fig. 3 is a section on the line 3—3, Fig. 1;

Fig. 4 is a view of the gripping plate.

In the drawing 1 indicates a wooden pole such as is used for telegraph, telephone and

other transmission purposes, said pole being set in the earth 2. The pole is illustrated as weakened by decay at the surface of the earth as shown at 3, this being a condition which frequently exists in poles that have been set for a few years.

My improved reenforcing means comprises two reenforcing means of special construction which are adapted to be driven or set into the earth on opposite sides of the pole and then clamped to the pole. The reenforcing members are indicated generally at 4 and 5. Each member is formed of two angle iron elements 6 and 7 which are rigidly connected together to form a structure having a general T shape in cross section. The legs 8 and 9 of the angle iron elements are adapted to rest against the pole and they are preferably curved slightly to fit the curvature of the pole. The legs 10 and 11 extend outwardly in a radial direction.

Situated between the legs 10 and 11 is an anchoring plate 12, said plate and the legs 10 and 11 being rigidly secured together by means of rivets 13 or other fastening devices. The anchoring plate 12 is preferably considerably wider than the legs 10 and 11 and when in place the inner edge 14 thereof extends inwardly beyond the angle iron members and thus forms a rib which is embedded in the pole 1. Said anchoring plate 12 also extends outwardly beyond the angle iron members and it forms a relatively wide resisting surface which becomes firmly embedded in the earth.

The reenforcing members will preferably be about six feet long although the length may vary according to the requirements. When in use about two-thirds of each member will be embedded in the earth, the other third projecting above the earth.

Since one purpose of the anchoring plates 12 is afforded an increased anchoring surface in the earth it is not necessary that these plates should extend the full length of the angle iron members and I have accordingly illustrated them as extending from about the point where the reenforcing members emerge from the earth nearly to the bottom thereof. At the lower end of each reenforcing member I will preferably employ a gripping plate 15 which is secured between the legs 10 and 11 by means of suitable rivets. The edge 16 of this gripping member projects inwardly beyond the angle iron members and is serrated or toothed as

shown, the teeth becoming embedded in the pole and being of such a shape as to resist the upward movement of the reenforcing members. The lower ends of the reenforcing members are tapered or pointed as shown so as to enable them to more freely be driven into the earth at the side of the pole.

The reenforcing members are clamped to the pole by means of special clamping devices, which are described and claimed in my co-pending application Serial No. 50,319, filed August 14, 1925. Each clamping device consists of a plate 17 having a plurality of holes 18 and two dogs 19, each having a threaded end 20 adapted to extend through the radial legs 10 and 11 of the angle iron members and to have a clamping nut 23 screw-threaded therethrough and also having an inwardly-bent sharpened end 21 adapted to enter one of the holes 18 of the plate 17 and to be driven into the pole.

In applying the reenforcing members to a pole which has already been set said members may be driven in place at opposite sides of the pole after which the clamping members will be applied. This is done by inserting the threaded ends of the dogs through apertures in the radial legs of the angle iron members and screwing the clamping nuts partially onto said ends and then driving the pointed ends 21 of the dogs through the apertures 18 and into the pole after which the nuts 23 may be tightened to rigidly clamp the reenforcing members to the pole. This clamping construction has the advantage that it is anchored to the pole and thus prevents the pole from twisting. Any twisting of the pole is also resisted by the ribs 14. This device can be readily and inexpensively manufactured as the angle iron elements may be commercial angle iron which have had one of their legs bent slightly to fit the curvature of the pole and the anchoring plate and gripping plate can be easily made from sheet iron or steel.

26 indicates a filling plate which is inserted between the legs 10 and 11 of the angle iron above the anchoring plate 12.

The legs 10 and 11 of the reenforcing member are shown as provided with apertures 27 adjacent the lower end. These would be used in case the reenforcing members are applied to the pole before it is set. Under such circumstances the clamping members would be employed to clamp the lower end of the reenforcing member to the pole as well as the upper end thus clamping the reenforcing members at both ends. The holes 27 provide means for applying the clamping dogs.

I claim:

1. A reinforcement for poles comprising two reenforcing members adapted to be set into the earth at opposite sides of a pole, means for clamping said members to the pole, each member comprising two angle iron elements rigidly secured together to form a reenforcing member having a T shape in cross section, one leg of each element adapted to rest against the pole and the other leg extending outwardly in a radial direction from the pole, an anchoring plate interposed between the radial legs, one edge of said plate extending inwardly beyond the angle iron members to form a rib which is embedded in the pole and the other edge of said plate extending outwardly beyond the radial legs and forming an anchoring surface which is embedded in the earth.

2. A reinforcement for poles comprising two reenforcing members adapted to be set into the earth at opposite sides of a pole, means for clamping said members to the pole, each member comprising two angle iron elements rigidly secured together to form a reenforcing member having a T shape in cross section, one leg of each element adapted to rest against the pole and the other leg extending outwardly in a radial direction from the pole, an anchoring plate interposed between the radial legs, one edge of said plate extending inwardly beyond the angle iron members to form a rib which is embedded in the pole and the other edge of said plate extending outwardly beyond the radial legs and forming an anchoring surface which is embedded in the earth, said anchoring plate extending nearly to the bottom of the angle iron members and a gripping plate between the angle iron members below the anchoring plate and provided with teeth adapted to have a gripping engagement with the pole.

3. A reinforcement for poles comprising two reenforcing members adapted to be set into the earth at opposite sides of a pole, means for clamping said members to the pole, each member comprising two angle iron elements rigidly secured together to form a reenforcing member having a T shape in cross section, one leg of each element adapted to rest against the pole and the other leg extending outwardly in a radial direction from the pole, an anchoring plate interposed between the radial legs, said anchoring plate extending outwardly beyond said legs and forming an anchoring surface which is embedded in the earth.

In testimony whereof, I have signed my name to this specification.

GEORGE B. SPRING.
